ATTORNEY.

UNITED STATES PATENT OFFICE.

AEGIDIUS DÜSTERWALD, OF HALLE-ON-THE-SAALE, GERMANY.

ELASTIC SUPPORT FOR FLAT FEET.

1,206,519.

Specification of Letters Patent. Patented Nov. 28, 1916.

Application filed August 30, 1916. Serial No. 117,743.

To all whom it may concern:

Be it known that I, AEGIDIUS DÜSTERWALD, a subject of the King of Prussia, and resident of Halle-on-the-Saale, Germany, have invented new and useful Improvements in Elastic Supports for Flat Feet, of which the following is a full, clear, and exact specification.

The subject of the present invention is 10 an elastic insertion support for flat feet with a pocket which serves for the reception of interchangeable elastic supporting means.

According to the invention the supporting means consist of elastic rubber tubes which are held in place by a thin metal plate and secured from slipping out by a relatively rigid sole plate provided with a re-curved retaining edge.

20 An embodiment of the present invention is illustrated in the accompanying drawing, wherein:

Figure 1 is partially a side elevation, and partially a longitudinal section thereof; 25 Fig. 2 is a plan view corresponding to Fig. 1; Fig. 3 is an enlarged cross section of the support through its pocket; Fig. 4 is a detail view of the plate for holding the rubber tubes; Fig. 5 is a detail view of the 30 rigid sole plate.

Upon a flat sole A is placed a suitably cut pocket a of leather or the like, composed of two halves sewn one upon the other. The lower part of the pocket is 35 flat and its upper part arched, so that it projects up under the inner side of the foot and slopes downward from that point in crescent shape to the lower half. The pocket a is adapted to receive several elastic rubber tubes b, the arrangement of which 40 transversely to the longitudinal axis of the foot is illustrated in Figs. 1 and 2. These rubber tubes are cut off vertically at one end and sloping at their other end corresponding to the arched form of the pocket a. They are attached to one another by 45 means of a string h or the like and are secured in the pocket a by means of the metal plate c, which is bent upward behind and in front (Figs. 1, 2 and 4), which plate is 50 provided in the middle part with two holes (Fig. 4) in order to be secured to the sole A by rivets. The space b (Fig. 1) remaining free in front and behind the rubber tubes b can be filled with felt or any other 55 suitable cushioning material.

The sole A is provided beneath the lower surface of the pocket a with a metal plate e (Fig. 5) which has for its purpose to give to the entire device a firm support and 60 a certain rigidity to insure it sitting well in the shoe.

The metal plate e upon which the retaining plate c is riveted is, as shown in the drawing, bent up at a right angle at the 65 edge corresponding to the inner side of the foot at the point e¹, and is thereby strengthened. Moreover the up-turned flange e¹ on the metal plate e which lies adjacent to the vertically cut ends of the rubber tubes is 70 intended to prevent the escape or the side-wise displacement of these tubes. The metal plate e lies between two leather or fabric layers f of which the upper one forms the underside of the pocket a and 75 also together with the plate e forms the sole A, the outline of which is adapted to the form of the foot.

The flat foot support thus composed forms a soft, excellent elastic support for 80 the foot in place of a rigid support. By the compression of the tubes b through the tread of the foot the air is pressed out of the tubes and when the foot is raised it is again drawn in. If the rubber tubes 85 lose their elasticity in the course of time they can always be replaced by new ones at slight expense, inasmuch as the upper side of the pocket a (Figs. 1 and 3) can be lifted after cutting the seams, the old 90 tube be removed and a new one inserted.

What I claim is:

1. An elastic support for flat feet, consisting of a sole plate, an arched pocket 95 fastened on the upper side of said sole plate and elastic rubber tubes within said pocket, said tubes being cut off vertically at one end and sloping at their other end, said sole plate being provided with an upright flange serving as a stop for the said 100 vertically cut off ends of the rubber tubes, substantially as described.

2. An elastic support for flat feet, consisting of a sole plate, an arched pocket fastened on the upper side of said sole 105 plate, elastic rubber tubes within said pocket and a metal plate fixed to said sole plate and arranged to hold the rubber tubes in place within the pocket, substantially as described.

3. An elastic support for flat feet, consisting of a sole plate, a covering therefor,

an arched pocket fastened on the upper side of said sole plate, elastic rubber tubes within said pocket and a cushioning filling in the free space of the pocket around said rubber tubes, substantially as described.

5 In witness whereof I have hereunto signed my name this 10th day of August,

1916, in the presence of two subscribing witnesses.

AEGIDIUS DÜSTERWALD.

Witnesses:

RUDOLPH FRICKE,
R. H. SAGLE.
